UNITED STATES PATENT OFFICE

159,219

HOOD ORNAMENT

Harry Martin Martin, Fort Lauderdale, Fla.

Application May 20, 1948, Serial No. 146,477

Term of patent 3½ years

(Cl. D14—18)

To all whom it may concern:

Be it known that I, Harry Martin Martin, a citizen of the United States, residing at Fort Lauderdale, in the county of Broward and State of Florida, have invented a new, original, and ornamental Design for a Hood Ornament, of which the following is a specification, reference being had to the accompanying drawing, forming part thereof.

Figure 1 is a side elevational view of a hood ornament, showing my new design;

Figure 2 is a top plan view thereof;

Figure 3 is a front elevational view of the same;

Figure 4 is a cross-sectional view, taken substantially in the plane of the line 4—4 of Figure 1, and

Figure 5 is a fragmentary cross-sectional view,

taken substantially in the plane of the line 5—5 of Figure 2.

The dominant features of my design reside in the portion shown by full lines.

I claim:

The ornamental design for a hood ornament, as shown and described.

H. MARTIN MARTIN.
